UNITED STATES PATENT OFFICE.

SAMUEL M. BROOKS, OF LAWNVILLE, TENNESSEE, ASSIGNOR OF NINE-TWENTIETHS TO J. M. SMITH, J. W. CROWDER, AND J. B. HARVEY, OF SAME PLACE, WILLIAM T. GALLAHER, A. L. MAY, AND L. N. HOLLOWAY, OF ROANE COUNTY, AND CAMEL JONES, OF WHEAT, TENNESSEE.

CAR-COUPLING.

SPECIFICATION forming part of Letters Patent No. 653,611, dated July 10, 1900.

Application filed October 19, 1899. Serial No. 734,121. (No model.)

To all whom it may concern:

Be it known that I, SAMUEL M. BROOKS, a resident of the city of Lawndale, Roane county, Tennessee, have invented a new and useful Improvement in Car-Couplers, which invention is fully set forth in the following specification.

My invention relates to car-couplers, and more especially to automatic car-couplers designed to automatically effect the coupling of railway and other cars.

The object of the invention is to produce a car-coupler which shall be efficient in operation, cheap to manufacture, and not liable to get out of order.

With this object in view the invention consists in a tumbler eccentrically mounted in a draw-head and normally supporting the coupling-pin, the tumbler being in position to be actuated by the coupling-link as it enters the draw-head, thereby automatically actuating the tumbler to release the pin, which latter thereupon falls under the action of gravity through the link into the proper seat in the draw-head.

The invention further consists of certain minor details of construction which will be hereinafter described and then pointed out in the claims.

One embodiment of the invention is shown in the accompanying drawings, wherein—

Figure 1 is a vertical longitudinal section of my automatic coupler with the parts in the position which they occupy just before the link has actuated the tumbler to permit the pin to fall into position to engage the link. Fig. 2 is a like view with the parts shown in the position which they assume when the pin has been withdrawn preparatory to uncoupling. Fig. 3 is a broken perspective view showing the parts in the position which they occupy when the coupling-pin is in engagement with the link.

Similar letters of reference are employed to designate similar parts throughout the several views.

In said drawings, A represents the draw-head, which has the usual longitudinal bore,

and B is a tumbler pivoted at b in a slot formed in the upper side of the draw-head, 50 said tumbler preferably having its pivot-pin b passing through an oblong slot b', formed therein. This tumbler is eccentrically pivoted, so that its center of gravity is to the rear of the pivot-pin b, that portion of the 55 front face of the tumbler lying opposite the bearing-pin b being a substantially-vertical face, which when the tumbler is in position to sustain the coupling-pin abuts against the front wall of the slot in which the tumbler is 60 pivoted. Projecting from the front face of the tumbler is a lip or lug B', which extends forward in the channel of the draw-head, and when the tumbler is in normal position (indicated in Fig. 1) said lip or lug B' is immediately under the coupling-pin C, having vertical play in an opening or vertical channel C', formed in an upward extension C² of the draw-head A.

C² is an opening extending through the 70 lower wall of the draw-head immediately beneath the opening C' and alined therewith.

The tumbler B has a slot b² formed therein, preferably in that portion of the tumbler lying immediately above the pivoted pin b, and 75 a slide or pin B² placed in said slot, said slide or pin having a flange or lip b³ projecting from the rear of the tumbler and a nose b⁴ projecting from the forward side of the tumbler into an opening C⁴, (shown in the walls of the channel C'.) The length of this slide is such that when the flange b³ is in engagement with the rear wall of the tumbler, as shown in Fig. 2, the nose b⁴ of the slide will project through the opening C⁴ and into the path of the pin C. 80 Immediately beneath the lug B' the tumbler has a rounded-out or cut-away portion B⁵, which is shaped to engage the rounded end of the link D when inserted within the draw-head, as shown in Figs. 1 and 3. Preferably 85 the tumbler has a suitable housing E formed on the upper surface of the draw-head in order to protect it from the entrance of dirt and other foreign substances, and the draw-head also has preferably formed in the bottom wall 90 thereof a small hole F for the escape of dirt 95

and other foreign substances that may enter the channel of the draw-bar and serve to obstruct the efficient operation of the parts.

- The operation of my device is as follows:
- 5 When it is desired to insert a link in the draw-head, the coupling-pin C is raised into the position shown in Fig. 1, when the tumbler by reason of its eccentric mounting swings forward, so that the lug B' rests under the pin C. Upon the link being inserted either by hand or by reason of another car coming into position to be coupled therewith the link D pushes the tumbler rearward, and the pin C falls from the position shown in Fig. 1 to that shown in Fig. 2. In case it is desired to uncouple two cars the pin C is raised from the position shown in Fig. 3 to that shown in Fig. 2, it being understood that the draw-heads of the two cars abut each other, so that the link D is pushing rearward upon the tumbler B, so as to force it into position shown in Fig. 2. When in this position the pin C is raised, whereupon the slide B² moves so as to project its nose b⁴ under the pin C, as is clearly shown in said Fig. 2, and the cars being thus uncoupled when the link D is withdrawn the tumbler B follows the link, presenting the lug B' in position to catch and support the pin C, as shown in Fig. 1, the slide B² being actuated by reason of the eccentricity of the tumbler, so as to withdraw the nose b⁴ from under the pin C, as will be clearly understood from an inspection of Fig. 1.

For the purpose of facilitating the ready entrance of the link into the draw-head the same is formed with an outwardly-flaring opening or mouth, and, if found desirable, the upper end of the opening C³ may be also similarly flared to facilitate the entrance of the pin C. The uncoupling of the parts may be performed by hand in the usual manner or by any suitably-mounted lever designed to

lift the pin and free it from engagement with the link.

If desired, the tumbler B may be provided with a lug b⁵, so positioned on the rear of the tumbler that it will engage the wall of the draw-head A when the tumbler has swung far enough to the rear to withdraw the lug B' from under the pin C. 45 50

Having thus described my invention, what I claim is—

1. The combination of the draw-head, an eccentrically-mounted tumbler having a part projecting into the path of the coupling-pin and another part projecting into the path of the coupling-link, with a slide mounted on said tumbler and having a nose projecting into the path of the pin, when the latter is raised and the tumbler is in its rear position. 55 60

2. The combination with a coupling-link, of a longitudinally-channeled draw-head, a coupling-pin moving vertically across the channel in the draw-head and engaging in suitable bearings in the walls thereof, a tumbler mounted to swing in a vertical plane within the channel of the draw-head and having a lug normally projecting into the path of the pin and above the path of the link, and a downwardly-projecting portion normally lying in the path of the link and in a plane below that of the lug, and a slide in said tumbler in a plane above the lug thereon, said slide having a part projecting into the path of the pin when the tumbler is in a position to withdraw said lug from out of the path of the pin. 70 75

In testimony whereof I have signed this specification in the presence of two subscribing witnesses.

SAMUEL M. BROOKS.
